United States Patent Office

Des. 188,106
Patented June 7, 1960

188,106

RADIO DIRECTION FINDER

Carl W. Sundberg, Bloomfield Hills, and Richard W. Figgins, Birmingham, Mich., assignors to Sperry Rand Corporation, a corporation of Delaware

Filed Dec. 24, 1959, Ser. No. 58,791

Term of patent 14 years

(Cl. D26—1)

FIG.1.

FIG.2.

FIG.3.

FIG.4.

Fig. 1 is a top plan view of a radio direction finder showing our new design;

Fig. 2 is a front elevation view;

Fig. 3 is a side elevation view taken from the right of Fig. 1; and

Fig. 4 is a rear elevation view.

We claim:

The ornamental design for a radio direction finder, as shown.
